DESIGN FOR A DISPLAY CASE FOR A WRIST WATCH

Benjamin Lazrus, Lawrence, N. Y., assignor to Benrus Watch Company, New York, N. Y., a corporation of New York

Application July 25, 1939, Serial No. 86,228

Term of patent 7 years

To all whom it may concern:

Be it known that I, Benjamin Lazrus, a citizen of the United States and a resident of Lawrence, Long Island, in the county of Nassau and State of New York, have invented a new, original, and ornamental Design for a Display Case for a Wrist Watch, of which the following is a specification, reference being had to the accompanying drawing forming a part thereof, wherein:

Fig. 1 is a front elevational view of a display case for a wrist watch embodying my design, with the case in closed condition;

Fig. 2 is a side elevational view of the same;

Fig. 3 is a front elevational view of the display case for a wrist watch, with the case in open condition;

Fig. 4 is a side elevational view of the same;

Fig. 5 is a top plan view of the display case for a wrist watch, in closed condition; and

Fig. 6 is a similar view with the case in open condition.

I claim:

The ornamental design for a display case for a wrist watch, substantially as shown.

BENJAMIN LAZRUS.
